The FIGURE is a perspective view of a record filing cabinet showing my new design.

The back side of the article has the same appearance as the front, while the side not shown is plain and unornamented.

The dominant feature of my record filing cabinet resides in the downwardly tapering front, rear and end walls of the bin portion, the tapering front and rear walls terminating at the bottom of the bin where they converge, in combination with vertically disposed, outwardly flaring leg panels which form a continuation of the end walls of the cabinet, all is shown.

I claim:

The ornamental design for a record filing cabinet, substantially as shown and described.
